UNITED STATES PATENT OFFICE.

HJALMAR G. CARLSON, OF WORCESTER, MASSACHUSETTS, ASSIGNOR TO ROCKWOOD SPRINKLER COMPANY OF MASSACHUSETTS, OF WORCESTER, MASSACHUSETTS, A CORPORATION OF MASSACHUSETTS.

NUT.

1,157,615.

Specification of Letters Patent. Patented Oct. 19, 1915.

Application filed February 1, 1913, Serial No. 745,527. Renewed April 22, 1915. Serial No. 23,214.

To all whom it may concern:

Be it known that I, HJALMAR G. CARLSON, a citizen of the United States, residing at Worcester, in the county of Worcester and 5 State of Massachusetts, have invented a new and useful Nut, of which the following is a specification.

This invention relates to the manufacture of nuts and particularly to that type of nuts 10 which are of relatively thin and of flat construction, used chiefly as lock nuts.

The principal objects of the invention are to provide a construction of nut which will enable a series or nest of nuts to be punched 15 out of a piece of sheet metal, each nut, except the largest thereof, being not only formed of the material taken out of the interior of a larger nut, but having its periphery coincident with the interior surface 20 of the next larger nut so as to avoid substantially all waste between these two surfaces, and yet provide a nut which will be capable of being properly screw threaded on the interior, and of being held between the 25 jaws of an ordinary wrench.

Further objects and advantages of the invention will appear hereinafter.

Reference is to be had to the accompanying drawings, in which—

30 Figure 1 is a plan of a sheet of metal with a series or nest of nuts cut from it in accordance with this invention; and Fig. 2 is a perspective view of one of said nuts.

In order that practical and durable nuts 35 may be produced each consisting of a single piece of hard metal, such as sheet malleable iron, steel, brass or the like, to give them such a form as to permit them to be cut out of sheet stock without waste, and yet have 40 the other necessary characteristics, the nuts, as indicated in Fig. 2, are made of a general cylindrical form, and on the outer surface thereof they are provided with longitudinal ribs *a*, that is, ribs parallel with the axes of 45 the nuts. These ribs in the present instance are shown as convex and substantially semi-cylindrical in form, but other shapes can be employed. They are, however, spaced apart around the periphery of the nut sufficiently 50 to permit the jaws of the usual wrenches to be inserted at the spaces so as to grip the nuts with the same force and effect as is the case with polygonal nuts. The nuts are also provided with internal recesses prefer-

ably of the same shape, size and location as 55 said ribs, whereby the ribs of a small nut are formed from the metal removed from the next larger sized nut in the formation of the recesses; also with this arrangement it will be seen that the nuts having the recesses are not materially weakened at these 60 points as the recesses although extending in beyond the normal surface of the nut are strengthened on the outer surface by the ribs.

From what has been said, it will be seen 65 that the external surface of the nut is capable of performing all the functions of the usual polygonal surfaced nut.

As to the interior of the nut it will be 70 seen that it can be tapped out so as to provide a discontinuous screw thread, this thread being interrupted at each of the recesses. This facilitates the cutting of the 75 thread in the first place as a material portion of the metal usually cut by the tap is missing, but especially for the reason that the chips produced by the screw cutting tap can be discharged through the recesses as the process of cutting goes on. Moreover 80 when the nut is in use the dirt and particularly metal chips and the like tend to be discharged through these recesses or rather to be forced out into them where they remain out of contact with the screw. Both 85 the ribs and recesses extend through the nut from side to side in a direction parallel with the axis thereof. A very important 90 advantage of this invention, however, lies in the fact that a series of these nuts can be punched out of sheet metal so as to utilize all of the metal except that which is inside the smallest and outside the largest one. In 95 this way a very high degree of economy is attained in the manufacture of these articles, nearly all the waste being eliminated, and moreover the punching operations are virtually reduced nearly fifty percent, because the operation of each punch or cutter performs two functions, namely, the shaping 100 of the entire exterior of one nut and of the entire interior of another. In this way the life of the dies is almost doubled, that is to say, they can be used to produce almost double the number of nuts heretofore possible.

Although I have illustrated and described only a single embodiment of the invention,

I am aware of the fact that modifications can be made therein by any person skilled in the art without departing from the scope of the invention as expressed in the claims. 5 Therefore, I do not wish to be limited in this respect, but

What I do claim is:—

1. As an article of manufacture, a nut consisting of a single substantially flat piece 10 of hard metal of a general cylindrical form both internally and externally, having a series of external ribs provided with spaces between them for the reception of the jaws of a wrench, and a corresponding series of 15 internal recesses, forming interruptions of the internal thread.

2. As an article of manufacture, a nut consisting of a single substantially flat piece of metal of a general cylindrical form, having a series of external ribs provided with 20 spaces between them for the reception of the jaws of a wrench, and a corresponding

series of internal recesses of substantially the same shape and relative location as said ribs. 25

3. As an article of manufacture, a circular sheet metal nut having external ribs and internal recesses, both ribs and recesses extending from one side of the nut to the other, and the recesses extending across the 30 entire interior threaded surface.

4. As an article of manufacture, a circular sheet metal nut having external convex ribs and internal concave recesses, both ribs and recesses extending from one side of the 35 nut to the other and registering with each other.

In testimony whereof I have hereunto set my hand, in the presence of two subscribing witnesses.

HJALMAR G. CARLSON.
